UNITED STATES PATENT OFFICE.

EDWARD W. CRAIG, OF CHICAGO, ILLINOIS.

PICTURE-FRAME.

No. 905,850.

Specification of Letters Patent.

Patented Dec. 8, 1908.

Application filed October 26, 1907. Serial No. 399,373.

To all whom it may concern:

Be it known that I, EDWARD W. CRAIG, a citizen of the United States, residing in Chicago, Cook county, Illinois, have invented 5 certain new and useful Improvements in Picture-Frames, of which the following is a full and correct specification, reference being had to the hereto accompanying drawing, forming a part hereof, and in which—

10 Figure 1 shows a plate or sheet of my material for making my said frames, in elevation, marked ready to be put into shape. Fig. 2 shows a transverse section of Fig. 1 in elevation and shaped into a frame. Fig. 3 15 shows a fragment of a corner and its back, of my said frame, in plan view. Fig. 4 shows, in plan view, on its rear side, a fragment of my material marked and cut and ready to put into position as shown in Figs. 2 and 3. 20 Fig. 5 shows, in sectional elevation, one side of a frame and a fragment of the back, forming, a part thereof, provided with a covering. Like reference letters show like parts throughout.

25 The object of my invention is to produce a picture-frame from thin sheets of cheap, light and strong material, such as straw-board, wood-veneering and like suitable material, which when veneered with a suitable paper 30 or textile material, which, when made according to my construction, may be made to assume the appearance of either expensive wood or metal, or fine gilding or bronzing, and the like. To attain said desirable end 35 I construct my said new picture-frame in substantially the following manner, namely: On a sheet of suitable straw-board *a* or card-board, wood-veneering, or like suitable material, is cemented a sheet *a'* of strong paper 40 or suitable textile. Said parts, thus prepared, form the stock from which my picture-frames are made. Said material is then cut to suitable sizes in rectangular forms, and on the back *a* are then scored four 45 sets of lines 1, 2, 3, and the squares *b'*, formed by the intersection of the lines 1, and 2, of adjacent sides, cut out, and from the lines 2 2 the ends of the elements or faces *c* are formed by cutting the mitral lines *d''*, which

may be extended to the edge *d³* or stopped at 50 the intersection of the line 3 so that the corners *d'* indicated by the broken outlines at the ends of the faces *d* may be retained for the purpose of increasing the gluing surfaces 55 in length.

The lines, or scores, 1, 2, 3, are cut into the back, or uncovered face of the backing *a*. When each corner of the said material is cut and scored as shown in Fig. 4 all the elements *d* are turned inward on their lines 3 as 60 on a hinge, and the faces *c* are turned in the same direction on their hinge lines 2, and the inner elements *b* are turned on their hinge lines 1 so as to stand at a right angle to the frame-back *a* and so that the several parts 65 assume the positions shown in Figs. 5 and 2; the glue *f* having been applied just before the parts are moved to their respective positions. We now have a picture frame provided with a back *a* integral with the frame 70 formed of the vertical sides *b* and the inclined sides *c* formed from the middle element held to place by the outer elements *d* charged with glue *f* adhering to the facing *a'*. Over the surface of this so constructed pic- 75 ture frame is then put a suitable finish; this may consist of paper *e* in imitation of wood in its surface and, again, the said frame may be finished in imitation of gold, or bronze and similar ornamental finish. The said frame 80 so constructed having all its parts, including the back integral, all cut from a single piece, forms an exceedingly strong yet very light structure into which a picture may be cemented on the framed or bordered surface of 85 *a'*. The facing *a'* also forms a hinge-element or part on which the frame-elements *b*, *c*, *d*, turn to their places on their hinge-lines 1, 2, 3, and said faces remain integral with each other and the back. The lines *b⁰* *b⁰* form 90 two sides of a square formed by the intersection of the sets of lines 1, 2; 1, 2, and form the meeting edges of the edge-pieces or faces of the frame-edges *b*. The fixing-element *d* is the outer element of the series, and it is the 95 one which is necessary to hold all the other elements *a*, *b*, and *c*, fixedly, to their respective places to complete the structure by glu-

ing it at *f* to the facing *a'* on the back *a* all as shown, element for element, each in its proper position.

What I claim is:—

- 5 A picture-frame comprising a back and thereto attached inner, middle, and outer hinge-connected frame-elements whereof said inner element is vertical to said back,

the middle element inclined from the top of said inner element to said back and the outer 10 element lies against said back and abuts against said inner element.

EDWARD W. CRAIG.
